CLAIM

The ornamental design for a plastic container, as shown and described.

DESCRIPTION

FIG. 1 is a top-front-right perspective view of a plastic container showing an embodiment of the claimed design; FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.

The broken lines in the figures represent features of the plastic container that form no part of the claimed design. All of the material from the parent application that is essential to the claimed design is included herein. Any material in the parent application that is not present herein forms no part of the claimed design.

1 Claim, 6 Drawing Sheets
